GENERAL THEATRES EQUIPMENT, INC., OF NEW YORK, N. Y., A CORPORATION OF
DELAWARE

IONIC BOMBARDMENT LIGHT SOURCE

Application filed December 4, 1930. Serial No. 499,898.

These improvements relate to light sources of the kind in which an incandescent surface is produced by ionic bombardment.

In my copending application Ser. No. 5 428,600, filed January 27, 1930, I have illustrated and described several different embodiments of lamps or tubes operating on the same principle as the one herein disclosed and have in that specification described fully the principles and operations involved in such a device.

In my copending application filed concurrently herewith as Ser. No. 499,897, I have described and claimed certain compositions 15 of matter useful with the present and said embodiments of the tube.

This application is directed chiefly to a lamp construction in which there is a third electrode useful under some conditions for 20 starting the operation. It presents also some other constructional variations from said first-mentioned copending application.

The prime object of the invention is to provide a light source of high intrinsic 25 brightness useful in recording or reproducing sound, in television, etc. Notable features of this tube are uniformity in action and its possibility of providing substantially a point source of light of high actinic value.

30 Other objects and advantages will appear hereinafter.

In the drawing Figure 1 is a vertical longitudinal section through my improved tube;

35 Fig. 2 is an enlarged fragmentary section showing parts of Fig. 1;

Fig. 3 is a greatly enlarged vertical longitudinal section through the cathode proper and its carrier shell, with a fragment of a 40 forming tool associated therewith and also in longitudinal section;

Fig. 4 shows the cathode elements as in Fig. 3 with the addition of a fragment of the surrounding sleeve; and

45 Fig. 5 shows conventionally the output of an amplifying circuit having associated therewith a starting circuit for the present lamp.

The device of Fig. 1 includes a base 10 in 50 which is set the elongated glass tube 11

turned inward at the base portion to form the stem 12 flattened at 13. A conductor 14 is connected to terminal 15 in the base, another conductor 16 is connected to base terminal 17, while a third conductor 18 is connected to base terminal 19. The construction thus described is according to common practice in the tube art.

Conductor 14 is connected to a conductor 20 which may approximately be a tungsten wire and which terminates in an exposed end or electrode at 21. A sleeve 22 of highly refractory material, such as magnesia, fits upon conductor 20. This electrode 21 is for starting the action of the lamp.

Conductor 16 has connected to it a conductor 23 (the cathode member) which terminates in the end portion marked 24 and which is about even with electrode 21. A sleeve 25 of the refractory material, as magnesia, is placed upon this cathode conductor 23.

To conductor 18 is secured a conductor 26 which should be of tungsten or other metal that seals with the type of glass used, and 75 to which in turn is secured a metallic band-like ring 27, suitably of nickel, and which encompasses the electrodes 21 and 24 with the electrode 24 in the center of the ring formation. This ring 27 is the anode.

Turning to Fig. 3 it will be observed that the front end portion 24 of cathode conductor 23 has a hollow interior filled with material 30. The wire 23, or at least the front end portion 24, is of some metal having a 85 high melting or fusing point such as tungsten or tantalum. I prefer tantalum for this rod or wire 23 or for the part 24 as that metal is easier to work than tungsten, and its fusing point is very high.

In the originally-squared-off end of rod 23, I bore the cylindrical recess 31 and fill same with the material of my said secondly-mentioned copending application, packing the same therein tightly and almost flush 95 with the end of the rod. That is to say, I pack in the material until the hole or recess 31 is almost filled. Then by means of a rotating tool as 33 (Fig. 3) having a conical recess 34, I swage or burnish over the side 100

walls 24a of the electrode holder or part 24. This has the effect of further compressing the material 30 in the recess, of forming retaining means for it, and further, of reducing the size of the opening as 29 through which the material 30 is exposed. I recommend a size of opening 29 ranging from six thousandths of an inch to ten thousandths of an inch in diameter.

10 The material 30 is the cathode proper. It has high electron-emissive properties and high heat-resisting properties. In its preferred form it consists of thorium oxide (ThO_2), 80% by weight, giving the mixture 15 high heat-resisting qualities, and barium oxide (BaO), 20% by weight, which is the highly-emissive element. These substances are mixed thoroughly together and maintained free of moisture as by carrying in a 20 dessicator until the time of use.

The barium oxide is first preliminarily heated to about seventeen hundred degrees Fahrenheit where ebullition takes place, the heating being continued until the mass becomes 25 quiescent in the crucible. It is then ground to a fine powder and mixed with the powdered thorium oxide.

The ring 27 is the anode. In my practice it glows at its outer margin with a typical 30 purplish corona glow. The exposed surface at 36, however, is intensely bright and incandescent due to ionic bombardment. The corona glow at the margin of anode 27 is not used by me. It may be shielded off in 35 various ways, as by a black coating 38 applied upon the outside of the end portion of tube 11 leaving a clear axial area at 39 through which the light from the cathode surface at 36 projects.

40 It is pointed out in this connection that the area of the material 30 exposed as at 36 may be only a few thousandths of an inch in diameter to produce a highly efficient light source for recording sound. I employ 45 an exposed area of the material of about ten thousandths of an inch in diameter and thereby obtain substantially a point source of light. The area of exposure may be varied within considerable limits, according 50 to the amount of light desired for a particular purpose.

It is fairly difficult to compact the cathode material in a recess only a few thousandths of an inch in diameter. Accordingly the 55 cylindrical recess 31 is made more in the nature of from twenty thousandths to twenty-five thousandths of an inch in diameter or as may be preferred. The spinning over of the free end of the electrode reduces 60 the opening 29 as may be desired, say to a diameter of ten thousandths of an inch.

Using preferably as low a potential as possible for the proper operation of the lamp the tube will ordinarily require a current flow of greater potential to get it start-

ed. To this end I have provided the starter electrode 21 between which and the cathode a discharge may occur of such nature as to produce initial ionization at the cathode at 36 and start the operation of the tube. I 70 show a circuit to accomplish such a discharge.

Turning to Fig. 5 the tube 40 and associated parts may be considered the output stage of an amplifying system. Output 75 primary 41 has a secondary 42 one end of which is connected through conductor 43 to the anode 27. The other end of secondary 42 is connected through conductor 44 to cathode 24. This arrangement provides a 80 circuit for exciting the lamp during the normal operations whereby the intrinsic brightness of the cathode proper varies in proportion to the variations of current in the output of the amplifier tube 40. Current for the lamp is supplied by battery 46 which with resistance 47 is bridged across the condenser 48. Resistance 47 may be variously from say one thousand ohms to ten thousand ohms and is adapted to regulate 90 the exciting current for the tube. The resistance 50 will be from say two hundred ohms to four hundred ohms and is preferably greater than the negative resistance of tube 11. 95

The starting circuit is bridged between the lamp current conductors 43 and 44, starting with conductors 51 and 52. Resistance 53 may be of the order of about ten thousand ohms. Conductor 54 leading from resistance 100 53 leads to a contact 55 which is shown contacting switch leaf 56 from which conductor 57 leads to plate 58 of condenser 59. The effect therefore is to charge plate 58 from line 43. 105

Conductor 52 leads to contact 60 shown as being in contact with switch leaf 61 connected by wire 62 to plate 63 of condenser 59, thus charging plate 63 from line 44.

This arrangement provides that when 110 plug 65 is in the open position, as shown, the current bridged across the lamp-exciting circuit is charging the plates of condenser 59. Now when plug 65 is moved forward leaf 56 makes contact with contact 66 115 connected by wire 66a to wire 52, and leaf 61 makes contact with contact 67, the latter being connected by a wire 68 to a resistance 69 of about two thousand ohms, and thence 120 through wire 70 to electrode 21.

It will thus be seen that when the plug 65 is moved to spread the leaves 56 and 61 condenser plate 63 is connected to electrode 21 while condenser plate 58 is connected to cathode 24. Under these conditions a discharge takes place between starting electrode 21 and cathode 24. The ensuing ionization 125 instantly starts the operation of the tube. When the operator desires to start he merely touches a switch button 130 repre-

sented by plug 65 to discharge condenser 59. Resistance 72 (of about twenty thousand ohms) and resistance 73 (of about ten thousand ohms) connecting lines 43 and 44 respectively with wire 70 maintains the starting electrode 21 at positive potential whereby on deeply negative swings of the signal-carrying current, should the lamp go out the operation will automatically re-start. After 10 the lamp is initially started and gets heated it will thus automatically re-start when temporarily put out. It is only when the lamp is cold that the starting feature is used.

The tube 11 is to be considered as being 15 filled with an inert gas such as nitrogen, argon, helium, etc., at some low pressure. In my practice with the particular form of lamp illustrated herein I employ nitrogen gas at a pressure of about forty millimeters 20 of mercury.

I claim:

1. In an ionic bombardment incandescent light source device of the character described, the combination of an electrode comprising 25 a holder for a cathode proper, said holder having a recess therein, a cathode proper comprising a material of substantially high ion-emissive properties and high heat-resisting properties and being in finely divided form tightly packed in said recess, and an anode electrode, said electrodes being in a receptacle having a clear space for light at a place opposite said recess, said receptacle containing inert gas.

35 2. In an ionic bombardment light source device of the character described, the combination of an electrode comprising a holder for a cathode proper, said holder having a recess therein, a cathode proper comprising 40 a material of substantially high ion-emissive properties and high heat-resisting properties and being in finely divided form tightly packed in said recess, and an anode electrode in the form of a ring surrounding 45 the axis of said recess and being adjacent to said cathode proper, said electrodes being in a receptacle having a clear space for light at a place opposite the cathode proper, said receptacle containing inert gas.

50 3. In an ionic bombardment light source device of the character described, the combination of an electrode comprising a holder for a cathode proper, said holder having a recess therein, a cathode proper comprising 55 a material of substantially high ion-emissive properties and high heat-resisting properties and being in finely divided form tightly packed in said recess, an anode electrode, and a third electrode adjacent to the 60 cathode for starting the operation of the device, said electrodes being in a receptacle having a clear space for light at a place opposite said recess, said receptacle containing inert gas.

65 4. In an ionic bombardment light source

device of the character described, the combination of a cathode proper element comprising a material of substantially high ion-emissive properties and high heat-resisting properties and being in tightly compacted 70 form, an anode element, and a starting electrode element adjacent to said cathode proper, said elements being in a receptacle having a clear space at a place opposite said cathode proper, said receptacle containing 75 inert gas.

5. In an ionic bombardment light source device of the character described, the combination of a cathode electrode having a small surface adapted to become incandescent under 80 ionic bombardment, an anode electrode, and a third electrode adjacent to said cathode and adapted to provide a spark for preliminarily heating said surface when the device is in normal position for use, said electrodes being within a container having therein an inert gas.

6. In an ionic bombardment light source device of the character described, the combination of a cathode having a small surface 90 adapted to become incandescent under ionic bombardment, and an anode in the form of a ring about an axis of said cathode substantially at right angles to said surface.

7. In an ionic bombardment light source device of the character described, a cathode member comprising a metallic holder having high heat-resisting properties and having an open ended recess therein, with annular walls defining said recess at its open end, 95 cathode material in said recess, said walls being formed over upon the material and serving as a partial cover and retaining means therefor.
